HAROLD W BROWN, OF ITHACA, NEW YORK, ASSIGNOR TO WESTINGHOUSE ELECTRIC AND MANUFACTURING COMPANY, A CORPORATION OF PENNSYLVANIA.

ELECTRICAL PROTECTIVE DEVICE.

1,168,054.

Specification of Letters Patent. Patented Jan. 11, 1916.

Application filed December 19, 1913. Serial No. 807,709.

To all whom it may concern:

Be it known that I, HAROLD W. BROWN, a citizen of the United States, and a resident of Ithaca, in the county of Tompkins and 5 State of New York, have invented a new and useful Improvement in Electrical Protective Devices, of which the following is a specification.

My invention relates to electrical protective devices and particularly to relays.

The object of my invention is to provide a relay which has adjustable torque characteristics.

The usual rotative type of relay has a 15 torque characteristic which is undesirable, because, toward the end of the rotative movement, additional work is imposed when contact is broken or made, and an additional torque is required to do this additional 20 work.

If a helical spring is attached to an arm of the rotatable member of a relay, the spring will exert a series of different torques for different angular movements of the rotatable member. These torques, when plotted against their respective angular displacements, form curves which approach sine waves in shape. A spring that is neither in compression nor tension when its 25 crank is at right angles to the line of action of the spring has two complete cycles of torque revolution, and if the stationary point of attachment of the spring is at a considerable distance, and the crank is comparatively short, the curve which represents 30 the stresses of the spring for its various positions is approximately a sine curve. If, however, the spring is in tension or in compression at all times during the rotation, 35 there is only one cycle per revolution, and if the spring tension is essentially unchanged the curve of its torque is a sine curve having only one cycle per revolution. Usually springs lie between these two extremes 40 so that if these two springs are applied to the same rotatable element, the resultant curve would be the combination of their respective single and double frequency curves. Since it is desirable to increase the 45 force tending to operate the contact members of a relay toward the end of its rotation the force during the remainder of the rotation being approximately constant, and since, by the proper combination and location of springs the resulting torque may be 50

made to conform to that which is desired, I provide an ordinary rotative type of relay with springs so arranged as to bring about the desired resultant torque curve. By properly advancing the phase angle between 60 the two springs, a curve showing a constant torque through a relatively long range may also be secured.

Referring to the accompanying drawings, Figure 1 is a front elevational view of a relay embodying my invention; Fig. 2 is a fragmentary top view of the relay shown in Fig. 1, shown partially in section and partially in plan; Fig. 3 is a side view of a relay embodying my invention, shown partially in section and partially in elevation, and Fig. 4 is a diagrammatic view of a circuit protected by a relay embodying my invention.

My invention comprises a case or housing 75 1, magnetic structures 2 and 3, and a frame work 4. The frame work 4 supports an armature 5 and a controlling mechanism 6 comprising a pivotally mounted stop 7 having an indicator attached thereto, a scale 8, 80 an actuating arm 9, a shaft 10, a gear wheel 11, a lever arm 12, springs 13 and 14, and a pivotally mounted indicator 15. The springs 13 and 14 are attached to the end of the lever arm 12 which is mounted on the shaft 85 10. The shaft 10 is operated by the gear wheel 11 through a pinion 16 on a main shaft 17 upon which is also mounted the armature 5. The spring 13 has its outer end attached to a stationary post 18, and the 90 spring 14 has its outer end attached to the pivotally mounted indicator 15. Upon the magnetic structure 2 are located a main coil 19 and an auxiliary coil 20, and upon the magnetic structure 3 are located the phase 95 coils 21 which are connected in a local circuit 22 with the auxiliary coil 20. The actuating arm 9 operates a movable contact member 23 which makes contact with a stationary contact member 24.

Referring now particularly to Fig. 4, my invention is used to protect a circuit 25 by tripping a circuit breaker 26 which is held in its closed position by an electromagnet 27 receiving current from a battery 105 28. The contact members 23 and 24 control the current that flows through the electromagnet 27. The member 23 is provided with a projection 31 that is engaged by the arm 12. The circuit breaker 26 is released 110

by a spring 29 which operates a latch 30 when the electromagnet 27 is deenergized.

The operation of my invention is similar to that of any of the well known types of relays, except that the torque is such that the opening of the circuit is made with a decisive break due to a gradually increasing torque curve.

The operation of my invention as here shown, is as follows: An overload upon the circuit 25 causes the coil 19 to take an excessive current that produces a magnetic flux in the magnetic structure 2. The flux thus produced induces a current in the coil 10 that is connected in series with the phase coils 21. Thus, the armature 5 will rotate as a predetermined load because of the rotative field that is produced in the air gap. The time of operation may be varied by 15 limiting the part of a rotation the disk will have to make before the contact is broken, and this may be done by moving the pivotally mounted stop 7 to the desired position, as indicated on the scale 8. The indicator 20 that is attached one end of the spring 14, may be shifted to any desired position on the scale 8, thus altering the shape of the torque curve and, consequently, the tripping current through certain ranges. 25 When the arm 9, as shown in Fig. 2 or the arm 32 as shown in Fig. 4, comes into engagement with the projection 31 from the movable contact member 23, it causes the disengagement of the contact members 23 and 30 24, thus breaking the circuit through the tripping coil 27 of the circuit breaker 26 to permit it to interrupt the circuit 25, as hereinbefore described.

While I have illustrated a preferred form 40 of my invention, it will be understood that it may be variously modified with respect to the number of and type of springs used and with respect to other structural modifications without departing from the spirit 45 and scope of the invention, as set forth in the appended claims.

I claim as my invention:

1. In an electrical protective device, the combination with a rotatable member, of a 50 plurality of springs angularly disposed with respect to each other and operatively connected to the rotatable member, and means for adjusting the relative tension of the said springs.
2. In an electrical protective device, the 55 combination with a relay and a plurality of resilient means angularly disposed with respect to each other for controlling the shape of the torque curve of said protective device.
3. In an electrical protective device, the 60

combination with a relay, of contact members, a plurality of resilient members angularly disposed with respect to each other for controlling the shape of the torque curve of said protective device, and means for adjusting the angularity of said resilient members. 65

4. In an electrical protective device, the combination with a relay of the rotative type, of contact members operated by said relay, resilient members eccentrically connected to the rotatable member of the said relay, and means for varying the angular displacement of said resilient members with respect to each other. 70

5. The combination with an electro-responsive device, of a plurality of resilient means for retarding the movable member of the said electro-responsive device, said resilient means being so disposed with respect to each other and to the movable member of the electro-responsive device that the movable member of the electro-responsive device has a substantially constant torque during the first part of its movement and a relatively greater torque during the latter part 80 of its movement. 85

6. In an electrical protective device, the combination with a relay of the rotative type, of means whereby said relay may actuate an auxiliary circuit, a plurality of 90 springs eccentrically connected to the rotatable member of said relay, and means for adjusting the angular displacement of said springs with respect to each other.

7. In an electrical protective device, the 95 combination with a relay of the rotative type, a plurality of springs eccentrically connected to the rotatable member of said relay and angularly displaced with respect to each other, and means for adjusting the relative tension on said springs. 100

8. A relay comprising a movable member, two resilient members operatively connected to the movable member and means for adjusting the relative position of the said resilient members with respect to each other. 105

9. An electro-responsive device comprising an armature, two springs operatively connected thereto and means for adjusting the relative tension of the said springs and 110 their angular relation with respect to each other.

In testimony whereof, I have hereunto subscribed my name this 28th day of November, 1913.

HAROLD W. BROWN.

Witnesses:

FRED L. CLARK,
D. V. PROCTOR.

It is hereby certified that in Letters Patent No. 1,168,054, granted January 11, 1916, upon the application of Harold W. Brown, of Ithaca, New York, for an improvement in "Electrical Protective Devices," errors appear in the printed specification requiring correction as follows: Page 1, line 32, after the word "torque" insert the word *per*; page 2, line 17, for the word "as" read *at*; same page, line 67, claim 4, for the word "tlectrical" read *electrical*; and that the said Letters Patent should be read with these corrections therein that the same may conform to the record of the case in the Patent Office.

Signed and sealed this 8th day of February, A. D., 1916.

[SEAL.]

R. F. WHITEHEAD,

Acting Commissioner of Patents.
